UNITED STATES PATENT OFFICE

162,279

JIG SAW

Hilmar A. Andresen and Raymond H. Andresen,
Chicago, Ill., assignors to Burgess Vibrocrafters,
Inc., Lake Zurich, Ill., a corporation of Dela-
ware

Application November 7, 1950, Serial No. 12,899

Term of patent 14 years

(Cl. D93—3)

To all whom it may concern:

Be it known that we, Hilmar A. Andresen and Raymond H. Andresen, both citizens of the United States, residing at Chicago, in the county of Cook and State of Illinois, have invented a new, original, and ornamental Design for a Jig Saw, of which the following is a specification, reference being had to the accompanying drawings, forming a part thereof.

Fig. 1 is a perspective view of the jig saw, showing our new design;

Fig. 2 is a side elevation; and

Fig. 3 is a front elevation thereof.

We claim:

The ornamental design for a jig saw, as shown.

HILMAR A. ANDRESEN.

RAYMOND H. ANDRESEN.
